INTERNAL COMBUSTION ENGINE

George Stephen Kammer, Budapest, Hungary

Application June 16, 1937, Serial No. 148,578
In Germany June 12, 1936

3 Claims. (Cl. 123—33)

The invention relates to internal combustion engines.

In reciprocating engines in which the ignition of the fuel is effected by bringing the temperature of the fuel in the working cylinder to the ignition temperature of the fuel by compression, it is necessary for achieving as complete combustion as possible to take precautions for a very intimate mixture of fuel and charging air. This mixture is usually 10 carried out by producing a current of air during the fuel admission.

Instead of the usual method of carrying out the compression in the working cylinder up to the occurrence of the ignition temperature of the fuel, it has already been proposed to produce this 15 current of air by the use of a space standing in communication with the operating cylinder by comparatively small ports or passages. This space was increased after the attainment of a 20 lower compression pressure by shifting a controlled auxiliary piston, so that in comparison with the pressure ruling in the working cylinder a lower pressure was formed in this space and the air flowed from the working cylinder through 25 the connecting ports into it. The fuel was then sprayed into the current of air thus produced and mixture took place without combustion. The final compression pressure, i. e. the pressure at which the temperature of the air reaches the ignition 30 temperature of the fuel, was then provided by the auxiliary piston as soon as the latter on its return stroke reduced the space in question, the fuel-air mixture being then displaced from this space into the working cylinder.

35 In this method of operation all the elements of the driving gear for the auxiliary piston had to be dimensioned to withstand the force due to the full compression pressure, so that this driving gear came out unduly large and heavy. On 40 one hand this denoted a considerable increase of weight and on the other hand the necessary rapid movement of the elements was made much more difficult by the large inertia forces.

In the engine according to the invention the 45 auxiliary piston has nothing to do with the compression, and thus its driving gear does not require to be designed for the force due to the final compression pressure, so that the various elements of this gear can be made much lighter and 50 the friction losses are also less.

According to the invention the working piston effects compression up to the attainment of the ignition temperature of the fuel, as is the case in the commonly known engines. On spraying in 55 the fuel there is a lower pressure in the space

standing in communication with the working cylinder, which was increased by the shifting of the auxiliary piston, and the inflow taking place from the working cylinder effects the mixture of fuel and air. Since, however, the air has already 5 reached the ignition temperature of the fuel, ignition now takes place, and combustion is effected almost exclusively in the auxiliary piston space. The pressure increases in this space in consequence of the combustion and becomes higher 10 than the pressure ruling in the working cylinder, so that, with the further assistance of the fall of pressure due to expansion during the working stroke, the combustion products are blown out from here into the working cylinder. Towards 15 the end of the expansion process, or during exhaust and scavenging, the auxiliary piston moves back, diminishing the space behind it, and pushes the contents of the space out into the working cylinder only having to overcome an inconsiderable 20 opposing pressure.

In the engine according to the invention the auxiliary piston, or one of the elements moving it, can be used at the same time to control the charging process by combining the piston or the element moving it with an element such as a valve, slide or the like closing and opening the charging air admission or the exhaust port.

The accompanying drawings show diagrammatically by way of example a constructional 25 form of a two-cycle engine according to the invention.

Figures 1 and 2 show the engine in section through the axis of the working cylinder, Fig. 1 at the upper dead centre of the working piston 35 and Fig. 2 at the lower one. Figs. 3 and 4 show the driving mechanism for the auxiliary piston, in side elevation and in front view respectively.

The working piston 2 moving upwards in the working cylinder 1 compresses the air previously introduced into the cylinder space until the final compression pressure is reached. While the piston is traversing the last 30 or 20 degrees before the upper dead centre (measured on the crank shaft) the auxiliary piston 3 has already been 40 pushed by a spring 13 into its lower position as shown in Figure 1, so that in the space 4 above the auxiliary piston 3 there is a lower pressure than in the cylinder 1, and the air compressed by the piston 2 flows at high speed into the space 4 45 through the connecting port 5 until the upper dead centre is reached. In the meantime the necessary quantity of fuel is sprayed into the current of air by means of the jet 6 in a direction parallel to the current as shown. The fuel 50

sprayed in ignites and burns, combustion taking place almost exclusively in the space 4. When the piston 2 has reached the upper dead centre the whole mixture is so to speak located in the space 4. In consequence of the combustion of the fuel the pressure rises, equalizes itself in the spaces standing in communication with each other and pushes the piston 2 to its lower dead centre doing work. As soon as the piston 2 partly uncovers the exhaust port 7, the auxiliary piston 3 is pushed up to the position of Figure 2 by the cam 14 driven from the crank shaft 15 by means of the toothed wheels 16 and 17, and acting on the rod 8. The volume of the space 4 is thus reduced nearly to zero and the combustion products located therein are pushed out into the cylinder 1 having only an inconsiderable pressure to overcome. At the same time the piston valve 9 mounted on the rod 8 uncovers the admission port 10, so that the scavenging and charging air flow through port 11 and space 12 into the cylinder space and drive out through the port 7 the combustion products located here, together with those displaced from the space 4. Hereupon the piston 2 commences its upward travel, closes the exhaust port, then the admission port, and compresses the fresh charging air present in the cylinder until it reaches the final compression pressure. Towards the end of the compression stroke the process described at the commencement begins afresh.

The fuel supply can also take place in any desired way differing from that shown, e. g. the jet 6 can also be arranged above the working piston 2 and the particles of fuel be led in the direction of the connecting port 5, or the fuel can be sprayed into the space 4 in countercurrent to the air current flowing into it. In some circumstances it is sufficient to place the fuel in a suitable hollow in the space 5.

In the constructional form shown in the drawings the admission port 10 on the side of the working piston is larger in the stroke direction than the exhaust port 7, so that it is only at a later point of time than the exhaust port that it is completely closed by the rising piston; the same effect can be just as well achieved by arranging the admission port higher than the exhaust port, or arranging several admission ports one above another.

The accurate time adjustment of the movement of the working piston 2 and of the auxiliary piston 3 in relation to each other is best effected in actual practice, namely in such a way that the fuel consumption is the lowest possible.

The movement of the auxiliary piston 3 can be displaced in time even during operation by means of a suitable arrangement, e. g. by employing a steeply pitched nut 18 rigidly connected to the toothed wheel 17 which in this case is movable on the shaft 19 of the cam 14. Since the pin 20 fastened to the shaft 19 lies on two sides against the steep screw surface of the nut 18, the shaft 19 will take part in the rotation of the toothed wheel 17. By shifting the bifurcated lever 22 pivotably mounted on the stationary pin 21, the toothed wheel 17 and the nut 18 can be axially displaced on the shaft 19, whereby the pin 20 is caused to slide over the screw surfaces of the nut 18, and the shaft 19 to slightly turn in respect to the toothed wheel 17. By a similar arrangement for instance when starting the engine the occurrence of the lower pressure can be displaced to a later point of time than when running normally, 75 and thus a higher compression can be achieved.

To control the admission and exhaust, valves or other elements can be provided, and the charging air can be compressed in the crank case or by means of a separate blower.

What I claim is:

1. A compression ignition engine comprising a working cylinder and working piston, an auxiliary cylinder, a piston valve therein for the admission of combustion and scavenging air, an auxiliary piston to vary the volume of the end of the auxiliary cylinder, a restricted communication between the end of the auxiliary cylinder and the working cylinder, common means for respectively operating the piston valve and the auxiliary piston to uncover the admission port and reduce the volume of the end of the auxiliary cylinder when the working piston is near the end of its expansion stroke, and to cover the admission port and increase the volume of the end of the auxiliary cylinder when the working piston is in position on its compression stroke producing compression pressures in the working cylinder which result in ignition temperatures, and a fuel injection nozzle located in the restricted communication between working cylinder and auxiliary cylinder and producing a fuel jet directed into the latter.

2. A compression ignition engine comprising a working cylinder and working piston, an auxiliary cylinder containing a piston valve for the admission of combustion and scavenging air, an auxiliary piston to vary the volume of the end of the auxiliary cylinder, a restricted communication between the end of the auxiliary cylinder and the working cylinder, a fuel injection nozzle located in the restricted communication and producing a fuel jet directed into the auxiliary cylinder, cam gear to open the admission piston valve and move the auxiliary piston to reduce the volume of the end of the auxiliary cylinder towards the end of the expansion stroke of the working piston, and a spring to close said piston valve and move the auxiliary piston to increase the volume of the end of the auxiliary cylinder when the working piston is in position on its compression stroke producing compression pressures in the working cylinder which result in ignition temperatures.

3. A compression ignition engine comprising a working cylinder and working piston, an auxiliary cylinder containing a piston valve for the admission of combustion and scavenging air, an auxiliary piston to vary the volume of the end of the auxiliary cylinder, a restricted communication between the end of the auxiliary cylinder and the working cylinder, a fuel injection nozzle located in the working cylinder and producing a fuel jet directed into the auxiliary cylinder, cam gear to open the admission piston valve and move the auxiliary piston to reduce the volume of the end of the auxiliary cylinder towards the end of the expansion stroke of the working piston, a spring to close said piston valve and move the auxiliary piston to increase the volume of the end of the auxiliary cylinder when the working piston is in position on its compression stroke producing compression pressures in the working cylinder which result in ignition temperatures, an exhaust port provided in the cylinder wall and uncovered by the working piston near the end of its outward stroke, and an admission port opposite the exhaust port but extending further than the exhaust port in the inward stroke direction.
